UNITED STATES PATENT OFFICE.

CHARLES H. ALGER, OF MANCHESTER, OKLAHOMA.

DISCONNECTING DEVICE FOR TELEPHONES.

1,207,463.

Specification of Letters Patent.

Patented Dec. 5, 1916.

Application filed February 2, 1916. Serial No. 75,820.

To all whom it may concern:

Be it known that I, CHARLES H. ALGER, a citizen of the United States, residing at Manchester, in the county of Grant and State of Oklahoma, have invented new and useful Improvements in Disconnecting Devices for Telephones, of which the following is a specification.

This invention relates to certain novel and useful improvements in devices for disconnecting telephone instruments from the line wires and has particular application to a manually operable disconnecting device.

15 In carrying out the present invention, it is my purpose to provide a disconnecting device of the class described whereby, in the event of an electrical storm or the like the telephone instrument may be disconnected 20 from the line manually and the line wire connected to the ground so that a lightning discharge or other high tension current traversing the line may be grounded.

It is also my purpose to provide a disconnecting device for telephone instruments which may be located upon the exterior of the dwelling house or other structure in which a telephone instrument is installed and operated from the interior of such 30 structure, and wherein the component parts will be so arranged and correlated as to reduce the possibility of derangement to a minimum and operate efficiently and effectively under all conditions.

35 With the above and other objects in view, the invention consists in the combination, construction and arrangement of parts set forth in and falling within the scope of the appended claims.

40 In the accompanying drawings:—Figure 1 is a vertical sectional view through a disconnecting device constructed in accordance with my present invention, the same being shown installed. Fig. 2 is a horizontal sectional view on the line 2—2 of Fig. 1. Fig. 45 3 is a vertical sectional view on the line 3—3 of Fig. 1.

Referring now to the drawings in detail, 1 designates a portion of a building wall 50 and formed in such wall is an opening extending from the inner side of the wall to the outer side thereof. Disposed within this opening is a bushing 2 of insulating material and secured to the inner side of the wall 55 is a plate 3 formed with an opening coaxial

with the bushing 2, while secured to the outer surface of the wall is a box-like casing 4 having the back wall thereof formed with an opening in alignment with the bushing. Fastened to the inner surface of the back 60 wall of the casing 4 below the opening therein is a bracket 5 of some suitable construction, and secured to the bracket 5 adjacent to the outer end thereof and projecting outwardly from the bracket at right 65 angles thereto is a pivot pin 6.

7 indicates a vertical lever having a slot 8 formed therein between the ends thereof and through the slot 8 is placed the pin 6.

70 9 designates a vertical contact strip having the upper end bent back upon itself into substantially inverted U-shape, and the lower extremity offset. The upper bent portion of the strip is fastened to the inner side of the outer wall of the casing 4 adjacent to the wall of such casing while the lower offset portion is secured to the inner surface of the outer wall of the casing adjacent to the bottom wall and owing to the upper 75 bent end of the strip and the lower offset end, the central portion of the strip is spaced apart from the inner surface of the front wall, as clearly illustrated in Fig. 1 of the drawing. Slidably mounted within the bushing 2 is a rod 10 having one end projecting through the opening in the plate 3 and extending into the building, and the other end projecting through the opening in the back wall of the casing 4, and through 80 an opening in the upper portion of the strip 9. The end of the rod 10 within the opening at the strip is preferably tapered as at 11 so as to insure a snug contact between the rod and the strip. Surrounding the end 85 portion of the rod 10 within the casing 4 and capable of longitudinal adjustment along such rod is a tapering sleeve 12 formed of two longitudinal sections 13 and threaded on to the sleeve 12 is a collar 14 adapted, when moved in one direction, to bind the sleeve to the rod so as to hold the sleeve in the desired adjusted position, and when moved in the opposite direction to 90 release the sections of the sleeve so that the latter may be adjusted along the rod. One end of the spring 12 is connected to the upper extremity of the lever 7 through the medium of eyes 15 carried by the sleeve and lever respectively, while fastened to the 95 lower end of the lever 7 is an S-shaped con-

100

105

110

115

tact spring 16 adapted to move into and out of engagement with the contact strip 9.

The inner end of the rod 10 is equipped with a knob 17 whereby such rod may be moved longitudinally in one direction or the other and the inner end of the rod is adapted to be connected to one side of the telephone instrument by means of a wire 18, while connected to the upper end of the strip 9 is one of the line wires 19. The S-shaped contact spring 16 on the lower end of the lever 7 is connected to the ground through the medium of a wire 20.

Normally the tapered end 11 of the rod 10 is in engagement with the strip 9 while the S-shaped spring 16 is disengaged from said strip 9 and the lever 7 held in vertical position. In this condition of the device, the telephone instrument is connected to the line wire and may be used in the usual manner. When, however, it is desired to break the connection between the telephone instrument and the line wire and to ground the line wire, as in the event of a pending electrical storm, the rod 10 is moved in one direction by means of a knob 17 to disengage the tapered end 11 of the rod from the strip 9 and in this movement of the rod the lever 7 is swung about the pin 6 and engages the contact spring 16 with the strip 9. Thus, the connection between the line and the telephone set is broken and the line connected to the ground.

In the present instance, the wall of the opening in the plate 3 and the bore of the bushing 2 are formed with alining grooves 21 and connected to the rod 10 adjacent to the outer end thereof is a spring finger 22 adapted to lie within said grooves when the rod is at its limit of inward movement, and to frictionally engage the walls of the grooves to hold the rod in adjusted position. Upon the sliding of the rod to disengage the inner end thereof from the strip 9, the finger 22 springs out of the grooves and abuts the outer surface of the plate 3 to prevent acci-

dental movement of the rod in the opposite direction.

While I have herein shown and described certain preferred forms of my invention by way of illustration, I wish it to be understood that I do not confine myself to the precise details of construction herein described and delineated as modification and variation may be made within the scope of the claims and without departing from the spirit of the invention.

I claim:—

1. A device of the class described comprising a contact strip adapted for connection to a telephone line wire, a movable rod normally engaging said strip and adapted to be connected to a telephone set and capable of movement out of engagement with said strip, a lever pivoted for swinging movement and having one end connected to said rod and the remaining end connected to the ground and adapted to be swung into engagement with said strip in the movement of said rod out of engagement with said strip. 65

2. A device of the class described, comprising a contact strip adapted for connection to a telephone line wire, a movable rod normally engaging said strip and adapted to be connected to a telephone set and capable of movement out of engagement with said strip, a lever pivoted for swinging movement and having one end connected to said rod and the remaining end connected to the ground and adapted to be swung into engagement with said strip in the movement of said rod out of engagement with said strip, and an adjustable connection between said lever and rod. 75

In testimony whereof I affix my signature in presence of two witnesses.

CHARLES H. ALGER.
